Patent 2,330,728 is issued to Carl F. Mayer, Lakewood, Ohio, for a door for industrial ovens. The door is suspended from above and is guided by channels in the oven structure. It is designed to swing outward in case of an explosion, thus venting the oven. The door is also designed to swing back automatically when the pressure is released.

Patent 2,330,728 is issued to Carl F. Mayer, Lakewood, Ohio, for a door for industrial ovens. The door is suspended from above and is guided by channels in the oven structure. It is designed to swing outward in case of an explosion, thus venting the oven. The door is also designed to swing back automatically when the pressure is released.

UNITED STATES PATENT OFFICE

2,330,728

DOOR FOR INDUSTRIAL OVENS

Carl F. Mayer, Lakewood, Ohio

Application May 9, 1941, Serial No. 392,604

7 Claims. (Cl. 110—173)

This invention relates to industrial ovens of the kind used for drying paint, for baking cores, and for similar purposes, and it has to do more particularly with the doors of such ovens.

In ovens of the class to which reference is made, explosions occasionally occur, and unless provisions are made for instantly venting the oven of the excessive pressure thus created, damage to the oven structure proportional to the power of the explosion is practically certain to ensue.

The present invention pertains especially to vertically movable or so-called vertical lift doors for ovens of the class mentioned, and heretofore doors of this sort have been guided adjacent their lateral edges in ways or channels which restrict them to a definite course of movement and preclude any appreciable shifting of the door in a direction in line with and away from the door opening of the oven, such as would relieve excessive internal pressure.

In the case of ovens equipped with hinged doors, attempts have been made to meet the above condition by providing self-releasing latch mechanism, but when an explosion occurs in such an oven that is of sufficient force to overcome the resistance of the latch mechanism the doors are swung open with such violence as to endanger any workman who may be within reach thereof.

Among the objects of my invention are to provide, in an industrial oven structure, a door that is suspended from above and that will swing open enough to vent the oven in case of excessive internal pressure, such as that resulting from an explosion, and will then swing back by gravity toward closed position; to provide a vertical lift door for ovens of the kind in question that is suspended through flexible elements, such as chains, from a relatively high elevation so that the door has a pendulum action when blown open and will, by its own weight, not only close automatically, but be restrained from swinging further than is necessary to vent the oven thus eliminating, or at least minimizing, the danger of injury to anyone near the door; to provide if desired, or in some cases if required, a separable connection between the top edge of the door and the oven structure that assumes effective condition as the door closes and that serves as a hinge on which the door swings outwardly enough to vent the oven in the case of a minor explosion, or that separates and allows the door to swing open to a further extent in case of a major explosion; to so design and construct the separable

connection that it will direct the upper portion of the door toward closed position; to so relate the door to its flexible-suspension elements or chains as to cause it to hang in such a way as to enhance the sealing action between the lower portion of the door and oven; to provide, adjacent the lateral edges of the door, cooperating sealing means on the door and oven that are so inclined to the vertical course of movement of the door that, at the beginning of the upward travel of the door, said means will separate throughout the extent thereof, thereby to obviate friction between the sealing means, and to provide if desired, or if required under certain conditions, releasable or so-called explosion latch means for maintaining the lower portion of the door in sealing relation to the oven in opposition to practical excessive internal pressures, such as are encountered in the normal operation of the oven.

20 The foregoing objects, with others hereinafter appearing, are attained in the embodiment of the invention illustrated in the accompanying drawings wherein Fig. 1 is a front elevation of an industrial oven incorporating the invention; Fig. 2 is a fragmentary side elevation of the oven; Fig. 3 is a fragmentary plan, with certain parts broken away and other parts shown in section to better illustrate the seal between one of the edges of the door and the adjacent portion of the oven; Fig. 4 is a view similar to Fig. 2 but on a considerably larger scale and showing the top portion of the door and the adjacent portion of the oven in vertical section; Fig. 5 is a horizontal sectional detail, on a further enlarged scale, the same being taken on the line 5—5 of Fig. 4; Fig. 6 is a fragmentary perspective view of the oven and door showing the door spaced from the oven as might occur as the result of an explosion within the oven; and Figs. 7 and 8 are details, at right angles to each other, of the so-called explosion latch and the adjacent portions of the oven door and floor.

The oven proper, which for the purpose of claims 1 also term the enclosure, is designated generally by the reference numeral 1. As usual, the oven or enclosure consists of a walled structure fabricated of insulated panels and frame members, the front wall 2 having a door opening 3 that is surrounded by a frame 4. The lintel of the door frame includes a forwardly projecting ledge 5, best shown in Figs. 4 and 6. The oven or enclosure 1 is built upon a concrete floor 8, and rising from the floor along the opposite sides of the door opening 3, preferably with their lower ends embedded in the floor, are opposed

guides 9 each desirably consisting of an angle iron. The base flanges 10 of the guides 9 are disposed against the front wall 2 of the oven, while the flanges 11 extend outwardly from the plane of said wall at right angles thereto. Supported by the tops of the guides 9 is a built-up cross-beam 12, the same projecting at its ends somewhat beyond the guides, and rising from the beam are brackets 14 within which a shaft 16 is journaled. Secured to the shaft above the beam 12 are two chain-pocket wheels 17, and where the shaft projects beyond the left hand end of the beam 12, as the parts are viewed in Fig. 1, a similar but somewhat larger wheel 18 is fastened to the shaft. Associated with the latter wheel, and including a hub portion that is loosely mounted upon the shaft 16, is a unit 19 that includes eyes 20 through which an endless hand chain 21 is guided in operative relation to the wheel 18. This hand chain depends alongside a corner of the oven in convenient reach of a person standing on the floor. The frame structure comprising the guides 9 and cross beam 12 is suitably braced by diagonal ties 22 and structural elements 23, the latter being shown as extending horizontally rearwardly from the upper ends of the guides and as being rigidly attached thereto through gussets 24. The elements 23 may be anchored in any suitable manner, as to a framework at the opposite end of the oven structure, similar to that above described, provided the oven is of the kind having a door at each end.

Arranged for vertical movement between the side flanges 11 of the opposed guides 9 is a door 25. This door, like the walls of the oven, is constructed of insulated panels that are held in a marginal fabricated frame 26 from the top of which extends rearwardly a lip 27 (Figs. 4 and 6). When the door is down in closed position this lip 27 overhangs the ledge 5, and slots 28 in the former receive cam members 29 that are carried by said ledge and serve, first, to draw the top portion of the door rearwardly toward the oven and, secondly, as a separable hinge connection on which the door may swing outwardly at its lower end a limited distance under the influence of abnormal internal pressure, such as might result from a minor explosion within the oven. To better seal the joint between the lip 27 and ledge 5, a strip of packing material, indicated at 30 in Fig. 4, may be carried by one or the other of said parts. A strip 31 of similar material may also be applied to the bottom of the door, as shown in Figs. 4, 7 and 8, for contact with the floor 8.

Secured to the sides of the marginal frame 26 of the door are the base flanges 34 of sealing strips 35, shown as consisting of angle irons, which cooperate with similar strips 36 that are desirably adjustably connected, through their base flanges 37 and screws or bolts 38, to the forwardly extending flanges 11 of the guides 9. The sealing strips 35 and 36 at each side of the door are desirably inclined downwardly and outwardly at a suitable angle to the vertical plane of the front wall of the oven and are so related to each other that, when the door is down in closed position, said strips firmly contact each other throughout their entire lengths. Packing material may or may not be interposed between said strips and when used may be carried by one or the other. The purpose of adjustably connecting the strips 36 to the guides 9 is to avoid such accurate workmanship in production and fabrica-

tion of the parts as would otherwise be necessary.

Secured to the top of the marginal flange 26 of the door 25, as through anchorage means or 5 eyes 40, are flexible elements or chains 41 that extend upwardly and over the previously mentioned chain-pocket wheels 17 and beyond which they are connected to a counterpoise that is shown as made up of an inverted T-beam 42 to 10 which the elements or chains 41 are attached and upon which are supported a plurality of units 43 that constitute a weight designated generally by the reference numeral 45. The anchorage means or eyes 40 are preferably so located transversely of the top of the marginal frame 26 and with such reference to the center of gravity of the door as to throw the door slightly off balance, so to speak, and in such a direction that as it is lowered to closed position the sealing strips 20 35 will contact the sealing strips 36 first adjacent their lower ends. As the door settles to closed position, the inner edges of the slots 28 in the lip 27 at the top of the door will ride down the inclined faces of the cam members 29 on the 25 ledge 5, thereby to urge the top portion of the door inwardly so as to insure contact between the sealing strips 35 and 36 throughout the vertical extent thereof. At the same time, the joint between the lip 27 and the ledge 5 will be sealed 30 by the packing element 30, as will also the joint between the bottom of the door and the floor by the packing element 31.

While the weight of the door may be sufficient in most cases to retain the door closed 35 against normal internal pressures, the door may be equipped with latch means that will automatically release in case of abnormally high internal pressures, such as those resulting from explosions. Hence, the term "explosion latch" which 40 I have applied to such means. For the sake of clearness I have omitted the latch means from all but Figs. 7 and 8. When used, one such means is located at the bottom of each lateral edge of the door, and as shown in detail in said 45 views, it consists of a flat latch bolt 47 that is guided through slots in brackets 48 that are welded or otherwise secured to the outer surface of the sealing strip 35. The bolt is urged downwardly by a compression spring 49 that surrounds 50 the bolt and is confined between the upper bracket 48 and a washer 50 that is adapted to be adjustably connected to the bolt so as to vary the tension of the spring as desired by the engagement of a cotter pin 51 on which the washer 55 rests in any one of several holes 52 in the bolt. The bolt is limited in its downward movement by the engagement of a pin 53 that is carried by the bolt with the top bracket 48. The lower end of the bolt is arranged to engage a keeper 55 having a part embedded within the floor 8.

The oven is suitably heated by means not shown. Such means may consist of the common and well known system of ducts, air heater and impelling means by which air is heated and circulated through the oven.

Having thus described my invention, what I claim is:

1. In combination with an enclosure having a door opening, a door for said opening, suspension means for the door that is operative to raise and lower the door between open and closed positions, means effecting a separable pivotal connection between the top portion of the door and the adjacent portion of the enclosure when the 75 door is in closed position, and self-releasing latch

means associated with the lower portion of the door that automatically assumes effective condition as the door closes for retaining the door in closed position against normal internal pressure, said latch means yielding to release the door to relieve excessive pressure within the enclosure.

2. In combination with an enclosure having a door opening, a door for said opening that is capable of movement in a vertical direction between open and closed positions and also capable of movement in a direction substantially in line with and away from said opening, operating mechanism situated above the upper limit of movement of the door, flexible means by which the door is suspended from said mechanism, and separable connections through which the door is pivotally connected adjacent its top to the enclosure when the door is in closed position, said connections yielding under the influence of excessive pressure within the enclosure to release the door and relieve said pressure.

3. In combination with an enclosure having a door opening, a door for said opening that is capable of movement in a vertical direction between open and closed positions, parts on the door along the top and bottom edges thereof for closing the joint between the door and enclosure along said edges, and means adjacent the lateral edges of the door for closing the joint between said edges and the enclosure when the door is closed, said means including members mounted on the door and enclosure, respectively, the members on the door having inwardly facing surfaces and the members on the enclosure having outwardly facing surfaces that contact with each other, the plane of said contacting surfaces being slightly inclined to the vertical course of movement of the door when the door is closed, and certain of said members being adjustable with respect to the element on which they are mounted.

4. In combination with an enclosure having a door opening, guides spaced outwardly from the opposite sides of the opening, a door for said opening that is capable of movement in a vertical direction intermediate said guides between open and closed positions and also capable of movement in a direction substantially in line with and away from said opening, parts on the door along the top and bottom edges thereof that close the joint between the door and enclosure along said edges, and means adjacent the lateral edges of the door for closing the joints between said edges and the enclosure when the door is closed, said means including elements mounted on the edges of the door and having inwardly facing sealing surfaces and elements carried by said guides and having outwardly facing sealing surfaces where-with the former surfaces contact when the door is closed, the plane of said surfaces being inclined downwardly and away from the enclosure and being so related to the vertical course of movement of the door that said surfaces separate at

the beginning of the upward movement of the door.

5. In combination with an enclosure having a door opening, a door for said opening that is capable of movement in a vertical direction between open and closed positions and also capable of movement in a direction substantially in line with and away from said opening, means suspending the door throughout its range of movement from an elevation above the upper limit of movement of the door, the relation between the door and said suspension means being such as will cause the door to hang in a position wherein its bottom is nearer the enclosure than its top, and separable connections including cam means that interengage as the door approaches closed position for directing the top of the door toward the enclosure.

6. In combination with an enclosure having a door opening, a door for said opening that is capable of movement in a vertical direction between open and closed positions and also capable of movement in a direction substantially in line with and away from said opening, means suspending the door throughout its range of movement from an elevation above the upper limit of movement of the door, the relation between the door and said suspension means being such as will cause the door to hang in a position wherein its bottom is nearer the enclosure than its top, means serving to cam the top portion of the door toward the enclosure as the door approaches closed position, and self-releasing latch mechanism carried by the door adjacent the bottom thereof for retaining the door closed against normal operating pressures within the enclosure and yielding to release the door and relieve higher pressures.

7. In combination with an enclosure having a door opening, guides rising on opposite sides of said opening, a door movable vertically between said guides between a lower position wherein the door closes the aforesaid opening and an elevated position wherein said opening is substantially uncovered, suspension means for the door that is operative to raise and lower the door between open and closed positions, an inwardly projecting lip extending along the upper edge of the door, an outwardly extending ledge along the lintel of the door for cooperation with said lip when the door is closed, sealing strips extending along the lateral edges of the door and having inwardly facing contact surfaces that are inclined downwardly and outwardly in slight angular relation to the vertical plane of the door opening, and similar strips carried by the guides and having contact faces for engagement with the contact faces of the former strips when the door is in closed position, certain of said sealing strips being adjustable with respect to the element by which they are carried whereby the angular relation between the strip and vertical plane of said opening may be varied.

CARL F. MAYER.
